United States Patent Office

Des. 181,194
Patented Oct. 15, 1957

181,194

GLOVE

Julius A. Higier, Johnstown, N. Y.

Application January 28, 1957, Serial No. 44,617

Term of patent 3½ years

(Cl. D3—11)

I claim:

The ornamental design for a glove, substantially as shown.
